UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 12,495, dated September 27, 1881.

Application filed August 9, 1881. Term of patent 3½ years.

To all whom it may concern:

Be it known that I, WINTHROP L. JACOBS, of East Orange, in the county of Essex and State of New Jersey, have invented a new and original Design for Carpets, of which the following is a specification.

This invention relates to a new and original design for carpets and similar fabrics; and it consists in the novel grouping and configuration of figures, hereinafter more fully described.

The accompanying photograph illustrates a face view of a carpet having my new design.

A is a fanciful flower having upwardly-projecting buds *a a*. On a stem projecting upward to the left of flower A is a large rosette, B. On another stem, *b*, that projects upward to the right of figure A, is a peculiar three-lobed leaf, C. On another stem, projecting to the right of figure A, is a fanciful flower, D. From the leaf C extends a forked stem, *d*, one branch of which supports a fanciful flower, E, and the other another fanciful flower, F.

G, H, and I are three very prominent fanciful flowers, connected together by series of

stems *e e*, which stems traverse the entire background and unite all the flower and leaf-like figures of the carpet into one connected design. These stems also bear lesser leaves, buds, and flowers, as shown.

The background of the carpet is composed of vertical and horizontal parallel lines *f g*, arranged at equal distances apart and made of equal lengths, but so that each pair of horizontal lines is interrupted by every alternate pair of vertical lines, and vice versa, as shown. The small squares between these lines are ornamented with dots, to resemble small rosettes.

I claim—

1. The design for carpets, consisting of the figures A B C D E F G H I *a b d e*, substantially as shown.
2. The design for carpets, consisting of the figures A B C D E F G H I *a b d e f g*, substantially as shown.
